2,393,821
A method of preparing a photographic resist for use in the production of fine lines, such as cross hairs, scales, grati-
cles, and the like, by exposing a photographic resist to light and then subjecting the exposed areas to a heat-
carbonizing treatment.

UNITED STATES PATENT OFFICE

Method and composition of producing fine lines photographically

André Schoen, Binghamton, N.Y., and Letha Lemon Patterson, Arlington, Va., assignors to General Aniline & Film Corporation, New York, N.Y., a corporation of Delaware

No Drawing. Application May 11, 1943.

Serial No. 486,544

This invention relates to the photographic reproduction of fine lines, such as the production of cross hairs used in gun sights and other observation instruments, as well as scales and grati-
cles, and in general to designs in which very fine lines are desired. The invention also relates to compositions useful in the production of such fine lines, and in the preparation of resists for producing fine lines by etching.

In general the production of cross hairs, scales and other designs with very fine lines has heretofore been accomplished by the costly process of engraving with diamonds or other fine cutting tools. Attempts to produce such designs by a photographic process have proven to be unsatisfactory for a number of reasons, such as lack of resolution, poor adhesion of the lines to the surface material, lack of resistance to abrasion, and poor chemical resistance of the light-sensitive coating applied to the surface.

Thus, the U. S. Patent to Karl Gundlach, #1,922,434, granted on August 15, 1933, refers to the unsatisfactory results obtained by the prior methods utilized in producing fine lines of the nature above referred to. In referring to prior photomechanical methods of etching glass, the patentee states that while photomechanical methods of etching glass have already been suggested, these methods, which are in most cases based on the application of light-sensitive asphalt, or of chromate colloid layers, entailed great disadvantages and, therefore, hardly can be used in practice, the reason being that the light-sensitive layers are either not sensitive enough, as in the case of asphalt, or not resistant enough against the influence of hydrofluoric acid, as in the case of the chromate colloid layers.

It is accordingly an object of our invention to overcome the deficiencies of the prior art processes.

It is a further object of our invention to provide an effective, simple, inexpensive and practical means for producing fine lines of the nature above referred to on glass, metal and other surfaces. Copper has been found particularly suitable as a metal base.

It is a still further object of the invention to produce etched lines on the above mentioned bases.

In general, hydrofluoric acid and fluorides diffuse through all the photographic resists known to the art. This is recognized by Gundlach and to overcome this defect Gundlach found it necessary to utilize a metallic layer under the chromate layer in order to obtain fine lines photograph-

ically. We, however, have discovered that the light-sensitive colloidal chromate layers in which the colloid is fish glue, gelatin or casein can be rendered resistant to attack by hydrofluoric acid and its salts by treating the colloidal layer after exposure to a light image of the fine lines to be obtained with tannic acid-containing substance, and then subjecting the exposed areas to a heat-carbonizing treatment.

Our invention, therefore, consists in a method of producing fine lines photographically, which consists in exposing a photographic resist to light and then subjecting the exposed areas to a heat-carbonizing treatment.

mixture is heated to the boiling point, for example, in a double boiler. When the albumen has completely coagulated and the solution cooled down to room temperature, it is filtered. The specific weight of the clear filtered solution is about 1.04. This solution is hereinbelow referred to as photo-engraver's glue solution.

An albumen solution comprising 20 gms. of dry albumen and 100 cc. of distilled water is prepared. The albumen is soaked in the water for about four hours and to the resulting solution is then added a small amount, for example, two drops of phenol or other suitable preservative. The solution is then filtered through cotton.

A solution comprising 4 gms. of ammonium bichromate and 100 cc. of distilled water is prepared.

A solution comprising 40 gms. of tannic acid and 100 cc. of distilled water is prepared by dissolving the tannic acid in the water with the aid of heat and then cooling to room temperature.

To prepare the sensitizing solution, three parts of the above prepared photoengraver's glue solution, one part of the albumen solution and one part of the ammonium bichromate solution are mixed thoroughly and then filtered, care being taken to carry out the mixing away from direct light and air as much as possible. However, conducting the preparation in a darkroom is not necessary.

A piece or plate of chemically cleaned and polished glass or other material on which the fine lines are to be produced is then coated with a thin coating of the sensitizing solution. Any well-known coating method may be utilized for this purpose, such as centrifugal coating, smear method, painting or other satisfactory coating procedure. The coated plate is then allowed to dry in the absence of extreme heat, direct sunlight and air currents, avoiding dust as much as possible. In this way, a light-sensitive chromate colloid layer is produced on the surface.

The scales or fine lines are obtained by exposing the sensitive layer to light through a fine line negative. For example, the exposure may be made through a contrasty negative of the fine lines to be obtained, using a 25 ampere arc lamp at two feet distance the exposure time being 2-3 minutes depending on the negative. This is only given as an example, and other times of exposure and types of exposure light may be utilized. To develop the image all that is necessary is to immerse the plate in a tepid water bath or wash under running water for five minutes. Care must be taken to insure that all unexposed sensitized material is washed away.

After developing, the plate is immersed for five minutes in the tannic acid solution. It is then again carefully washed, followed by a rinse in distilled water. The plate is then allowed to dry and the image is then heat-carbonized by exposing to heat until the maximum blackness of the image is obtained. Good results are obtained when an exposure at 450° F. for 30 minutes is utilized although other temperatures and periods of heating give equally good results. The fine lines so produced withstand the action of hydrofluoric acid and its salts. The lines also are resistant to abrasion and various solvents and cleaning fluids such as xylol. The lines show excellent resolution and the absence of graininess and roughness of edges common to prior methods of producing fine lines.

Although we prefer to use fish glue, gelatin

or casein may be utilized in the process in corresponding amounts. Likewise, instead of ammonium bichromate, there may be used potassium or sodium bichromate in equivalent amounts. The albumen may be omitted but improved results are obtained, particularly with respect to adhesion, when it is present in the light-sensitive layer.

The above embodiment of the process results in the production of fine lines and the products so obtained may be used directly as graticules, scales and cross hairs for technical and other purposes.

In the alternative embodiment, the fine lines are utilized as resists in the production of etched lines, scales and graticules on glass or on other inorganic bases such as copper. In photo-engraving and related processes where the image is etched into the base material, the chief problem is to find a resist which will withstand a certain amount of mechanical abrasion, adhere to the base and be impervious to the etching solution which is usually acidic in character. As pointed out above, some acids like hydrofluoric and its salts penetrate the usual photoengraving resists with ease and cannot be used when a photographic design has to be etched on glass. For this reason, the prior photoengraving resists cannot be used to produce fine lines by etching.

The prior art processes are unsatisfactory because in transferring very fine lines to glass or other base, the resist must of necessity be very thin in order to faithfully reproduce the fine details of the original which consists mostly of very fine lines, dashes or dots. Since the usual photoengraving resists are attacked by the acidic etching fluids, these fine lines are quickly attacked and the etched lines produced are not of high resolution but are ragged and not clearly defined.

For the production of fine lines, the resolving power of the light-sensitive coating must be extremely high to insure the faithful reproduction of microscopic detail. A photoengraving resist should preferably have a dark color which facilitates inspection prior to the application of the etching fluid.

In our alternative embodiment of producing fine lines, the same solutions and procedure are employed as in the first embodiment, except that for exposure, a contrasty positive is used to obtain a negative image of fine lines on the sensitized coating; that is, the image is washed away, leaving the surrounding area protected. Subsequent to the tannic acid treatment and carbonizing, the resist is dark in color which facilitates inspection and has great resistance to mechanical abrasion and to the selected etch. The plate is then treated with an appropriate etch which acts only in the area of the image, the resist, due to the tannic acid and subsequent baking treatment, possessing the novel property of withstanding the action of hydrofluoric acid and its salts. After the lines have been etched in the surface, the resist is then removed. The etched lines may then be filled in by use of any suitable black varnish.

By way of example, a more detailed description of this embodiment follows:

Example II

A glass plate chemically cleaned and polished is coated with the sensitizing solution prepared in the manner indicated in Example I. The coated plate is then exposed through a contrasty positive of the fine lines to be etched on the

glass base, and subsequently treated as in Example I with tannic acid, followed by heat-carbonization. The plate with the carbonized areas thereon acting as a resist is then treated with an etching solution of the following composition:

Ammonium bifluoride	grams	10
Barium sulfate	do	10
Water	cc	100

for a period of ten to fifteen seconds, although the time may be varied depending on the degree of etching desired.

The resist is then removed by immersing in a hot chromic acid solution. On the glass surface only the etched fine lines now remain. If a better visibility of the lines is desired, the etched lines may be filled in by the use of a suitable black varnish or any other suitable preparation.

The following is an example of the procedure as applied to the production of etched lines on a metal plate, such as copper:

Example III

The resist is prepared on a copper plate in the same manner as described in Example II above for its preparation on glass. The area of the image is then treated with a 35° Baumé solution of ferric chloride until the desired degree of etch is obtained. The resist is then removed by rubbing the plate with calcium carbonate.

In the above example of etching glass, any glass etching fluid may be utilized although the process is most effective with the use of ammonium bifluoride. However, hydrofluoric acid or any of its water soluble salts may also be used. Likewise, other etching fluids may be used for etching the copper or metal surfaces.

While several embodiments of the invention are herein described, it is to be understood that various modifications may be apparent to those skilled in the art without departing from the spirit and scope of this invention and we, therefore, do not wish to be limited by the precise details set forth, but desire to avail ourselves of such variations and modifications as come within the scope of the appended claims.

We claim:

1. A method of producing cross-hairs, graticules, scales and designs with fine lines on surfaces, which comprises coating a surface with a light-sensitive chromate colloid layer in which the colloid is selected from the group consisting of fish glue, casein and gelatin, exposing the layer to a light-projected image of fine lines, removing the unexposed areas of the layer, subjecting the exposed areas to a tannic acid-containing substance, and subjecting the tannic acid-treated areas of the layer to a heat-carbonizing treatment, whereby fine lines of high resistance to abrasion and chemical agencies, and high resolution, adhesion and density are obtained.

2. A process as in claim 1 in which the surface is glass.

3. A method of producing cross-hairs, graticules, scales and designs with fine lines on a glass surface which comprises coating a glass body with a light-sensitive solution composed of fish glue, albumen and ammonium bichromate, exposing the light-sensitive layer thus formed through a negative of the fine lines to be obtained, removing the unexposed areas of the layer by developing with water, subjecting the exposed areas of the layer to an aqueous solution of tannic acid, and subjecting the tannic acid

treated areas of the layer to a heat-carbonizing treatment until maximum blackness of the exposed areas is obtained, whereby fine lines of high resistance to abrasion and chemical agencies, and high resolution, adhesion and density are obtained.

4. A process as in claim 3 in which the carbonizing treatment is carried out by subjecting the tannic acid treated areas to a temperature of 10 about 450° F. for about thirty minutes.

5. A process for producing cross-hairs, graticules, scales and designs with fine lines on surfaces which comprises coating a surface with a light-sensitive chromate colloid layer in which the colloid is selected from the group consisting of fish glue, casein and gelatin, exposing the layer through a positive of the fine lines to be obtained, removing the unexposed areas of the layer, subjecting the exposed areas to a tannic acid-containing substance, subjecting the tannic acid-treated areas of the layer to a heat-carbonizing treatment, thereby converting the exposed areas into a resist, and subjecting to an etching solution those areas of the surface from 25 which the unexposed areas of the light-sensitive layer has been removed.

6. A process for producing cross-hairs, graticules, scale and designs with fine lines on glass surfaces which comprises coating a glass body

30 with a light-sensitive layer composed of an aqueous solution of ammonium bichromate, albumen and fish glue, exposing the layer through a positive of the fine lines to be obtained, washing out the unexposed areas of the layer with water, subjecting the exposed areas to an aqueous solution of tannic acid and subjecting the tannic acid treated areas of the layer to a heat-carbonizing treatment thereby converting the exposed areas into a resist, and subjecting to an aqueous etching solution composed of ammonium bifluoride and barium sulfate those areas of the glass surface from which the unexposed areas of the light-sensitive layer has been removed, and then removing the resist.

45 7. A process as in claim 6 in which the surface is composed of copper and in which the etching is carried out by means of an aqueous ferric chloride solution.

8. A composition for producing fine lines and 50 resists for etching of fine lines on surfaces which comprises the heat-carbonized reaction product of a tannic acid-treated, light-exposed mixture of a protein selected from the group consisting of fish glue, casein and gelatin, and a light-sensitive chromate, said composition being resistant to hydrofluoric acid and its salts.

9. A new resist for photoetching of fine lines 55 on surfaces comprising the heat-carbonized reaction product of a tannic acid-treated light-exposed mixture of fish glue, albumen and ammonium bichromate, said composition being resistant to hydrofluoric acid and its salts.

10. A composition for use in preparing a resist for photoetching of fine lines on surfaces comprising the reaction product of a protein selected from the group consisting of fish glue, gelatin and casein and a light-sensitive bichromate, said composition, on exposure to light and subsequent treatment with tannic acid followed by heat-carbonization, forming a resist which will withstand the action of hydrofluoric acid and its salts.

11. A body having on its surface fine lines, cross-hairs, scales and graticules composed of 75 the heat-carbonized reaction product of a tan-

nic acid-treated and light-exposed mixture of a protein selected from the group consisting of casein, gelatin and fish glue; and a light-sensitive chromate said reaction product being resistant to hydrofluoric acid and its salts.

12. A body having on its surface fine lines, cross-hairs, scales and graticules composed of

the heat-carbonized reaction product of a tannic acid-treated, light-exposed mixture of fish glue, albumen and ammonium bichromate said reaction product being resistant to hydrofluoric acid and its salts.
